UNITED STATES PATENT OFFICE

EDWARD HOTTER, OF CHICAGO, ILLINOIS

DIE CASTING MACHINE

Application filed May 22, 1930. Serial No. 454,531.

My invention relates generally to foundry equipment and has to do more particularly with die casting machines.

An object of my invention is to provide a die casting machine which will automatically bring the dies into and out of cooperative relation and will automatically cast the metal, insert and pull cores from the dies, and eject the casting from the dies.

Another object is to provide such a machine which will have a fixed die and a movable die, and wherein the movement of the movable die will be automatically arrested at each end of its stroke.

Still another object is to provide such a machine of simple and rugged construction, and certain and reliable in operation.

Various other objects and advantages will become apparent to those skilled in the art as the description proceeds.

Referring now to the drawings forming part of this specification and illustrating a preferred embodiment of my invention;

Fig. 1 is a side elevation of a die casting machine, embodying my invention;

Fig. 2 is a top plan view of the same;

Fig. 3 is a sectional view taken substantially on the line 3—3 of Fig. 2;

Fig. 4 is a sectional view taken substantially on the line 4—4 of Fig. 3;

Fig. 5 is a sectional view taken substantially on the line 5—5 of Fig. 4;

Figs. 6, 7 and 8 are sectional views taken substantially on the line 6—6, 7—7 and 8—8, respectively, of Fig. 1; and

Fig. 9 is a top plan view of certain cams forming features of my invention and adapted for actuating the movable die and the core pulling apparatus, respectively.

In the drawings, the numeral 10 represents a pot or receptacle adapted for holding molten metal which is mounted in a fire box 12. This receptacle may be heated by any suitable means, such as a gas or oil burner 13.

Spaced from the fire box 12, as best shown in Fig. 1, is a frame member 15, supporting a journal 16 for rotatably mounting a main drive shaft 17. Rotary motion may be imparted to the drive shaft by any suitable means (not shown). Arranged on one end

of the drive shaft is a beveled gear 18, (Fig. 6), meshing with a pair of pinions 19 and 19' loosely carried by a shaft 20. Splined to the shaft 20 is a two-faced clutch member 21, pivotally connected as at 22 to a lever 23, which in turn is pivoted to the frame 15, as at 24. The lever 23 is pivoted adjacent its other end to a link 25 which, as best shown in Fig. 6, is preferably formed in a pair of members pivoted to each other so as to permit a certain amount of lost motion therebetween. The link 25 extends through a guide sleeve 26 attached to the frame 15 and is pivoted as at 28 to a hand lever 29, which is pivotally secured adjacent its end, as at 30, to the frame 15.

Thus, it will be noted that a swinging movement of the lever 29 either to the right or left, as shown in Fig. 6, will result in bringing the clutch member 21 into cooperative relation with one or the other of the bevel gears 19 or 19', it being understood that these gears are provided with faces adapted to cooperate with the faces of the clutch member. As shown in Fig. 6, the clutch member is in cooperative engagement with the bevel gear 19'. As will become apparent later, this arrangement of the clutch and bevel gears 19 and 19' is provided so as to permit reversing the motion of the parts to be described.

Keyed to the shaft 20 is a pair of spur gears 32 and 32', which mesh with a pair of similar gears 33 and 33', mounted on a shaft 34. Rotatable with this shaft, as shown best in Fig. 8, is a worm 37 which meshes with a worm wheel 38, keyed to a shaft 39. This worm wheel has a pair of pins 40, which, as best shown in Fig. 6, extend from a face of the wheel into the path of a lug 42 which projects laterally from one side of the lever 23. The purpose of this arrangement, as discussed more fully below, is to automatically throw the clutch 21 into neutral position at certain predetermined points in the operation of the machine.

As best seen in Fig. 3, the shaft 39 is journaled in bearings 44 and 44' carried by the frame 15, and has secured to the central portion thereof cranks 45 and 45', connected by a crank pin 47, which extends through a pair

of cam plates 50 and 51. The plate 51 is provided with a curved cam slot 51' and the plate 50 is provided with an oppositely curved cam slot 50', the crank pin 47 riding in both these slots and being secured by nuts or the like at opposite ends of the pin.

As will be seen from Fig. 9, the curved central portions of the cam slots are on arcs struck from the axis of the shaft 39, while the end portions of the slots extend substantially at right angles to the direction of movement of the cam plates. From this, it will be seen that the movement of the pin 47 from the position shown in Fig. 9 in either direction about the axis of shaft 39 will first cause a movement of the cam plate 51 to the right and later a movement of the cam plate 50 in the same direction; while on the return movement of the pin 47, the cam plate 50 will be first shifted to the left, and later the cam plate 51 will undergo a movement in the same direction.

The cam plate 50 is slidable on rods 50^a and 50^b carried by the frame 15 and a stationary frame 60, and has secured thereto a rod 53 (Fig. 3) which is threaded into a cylindrical member 55, the screw being secured by means of nuts 56 or the like within the cylindrical member, and an adjusting nut 57 being provided outside the cylindrical member so as to be readily accessible. The cylindrical member 55 extends through a cylindrical guide sleeve 59, Fig. 3, which is secured by bolts or the like to the stationary frame 60. Secured to the sleeve 59 opposite the frame 60 and extending through a slot 59^a in sleeve 59 and a slot 55^a in cylindrical member 55 is a bar 61, for a purpose which will presently be described, this bar being carried by a pair of adjusting screws 61' threaded through a flange 59' on sleeve 59. The cylinder 55 also extends through a stationary guide frame 63 and has mounted on its outer end a die carrier 65 which is slidably mounted on a plurality of guide rods 66^a, 66^b, 66^c and 66^d, Fig. 4, these rods being secured to the frame 15 at one end and to the fire box 12 at the other end. Detachably secured to the die carrier 65 is the movable section 68 of a suitable die which may be of any desired type according to the work to be cast.

The member 65 has a substantially central aperture through which extends a slidable plunger 69, this plunger having attached to the forward end thereof an ejecting member 70 (Fig. 3). This ejecting member may be of any well known or suitable type, and it will be noted that when the die carrier 65 is moved backwardly or to the right in Fig. 3, the plunger 69 will abut against the bar 61 and the ejector will thus be brought into engagement with the work and the latter will be ejected from the movable die member 68.

A fixed die member 72 adapted to cooperate with the movable die member 68 is secured

to a frame 73 attached to the wall of the fire box 12.

The cam member 51, which will be designated as the core-pulling cam, is guided by the cam 50, as best seen in Fig. 6, the cam 50 being channeled to seat cam 51, and said cam member 51 is secured to a pair of rods 51^a and 51^b which extend through the guide frame 60. These rods are secured at their forward ends to a crosshead 74 carrying sleeves 75 and 75', which in turn carry rods 76 and 76'. As shown best in Figs. 4 and 5, the rods 76 and 76' are slidably mounted in bearing blocks 77 carried by a frame 78 which is supported by the rods 66^a, 66^b, 66^c, and 66^d, and are provided with rack teeth 80 adjacent one end thereof, these teeth cooperating with elongated pinions 81. Each pinion 81 actuates a core-pulling member 82, the latter being provided with rack teeth cooperating with the pinion. The numerals 83 represent cores which are inserted and withdrawn by means of the core pulling mechanism just described.

The rods 76 and 76' which actuate the core pullers may be adjusted relative to the cross head 74 by means of nuts 84 (Fig. 2). It will be noted by reference to Fig. 5 that the rack teeth 80 formed on the rods 76 and 76' do not extend entirely to the end of these rods, the latter being blank or untoothed as indicated at 80'. The purpose of this construction is to permit, by adjustment of the rods 76 and 76' by means of the nuts 84, the insertion and pulling of cores of different lengths by the respective rods 76 and 76'. It will be obvious that the untoothed portion 80' of the rods results in lost motion after the teeth 80 have passed over the pinion 81, so that the pinion will be rotated only to a certain extent, according to the initial adjustment of its operating rod 76 or 76'.

As shown in Figs. 4 and 5, the core-pulling member 82 can be adjusted vertically lengthwise of the elongated pinion 81 and held in adjusted position by means of a plate 85 formed to embrace opposite walls of the frame 78 and bearing block 77 and slotted crosswise to seat the rack bar 82; said plate being formed with vertical slots 85' through which pass clamp screws 85^a. Furthermore, it will be seen that the core-pulling member 82 is provided with a core-gripping head 86, which is elongated transversely of the direction of the pinion 81, so that the core may be positioned at various points thereon. By means of this arrangement, the core puller may be adjusted at any desired position to accommodate various types and locations of cores.

Fast on the upper end of shaft 39, as best seen in Fig. 3, is a crank 87 carrying a pin 88 which is movable in a slot 90 of a cam member 91. This cam member is connected by means of a stem 91' and cross head 92 (Fig. 2) to rods 93 and 93', which slidably ex-

tend through the frames 60 and 73. To the cam is connected a rearwardly extending rod 95 which slides through a boss 96 attached to the frame 15.

Referring now to Figs. 1, 2 and 7, the threaded ends of rods 93, 93' forwardly of the frame 73 are passed through ears 100 of a frame 102, which, as best seen in Fig. 2, is H-shaped in plan view, the ears 100 being formed on opposite ends of one leg of the H, and the rods being locked to the ears by nuts 100'. This frame is slidable on rods 104 and 104' which are supported by means of a casting 105 above the fire box 12. Secured to the web portion 107 of the H-frame 102 as by means of bolts 108 is a vertically disposed H-shaped bracket 110, the latter depending from the frame 102. The bolts 108 pass through vertical slots 113 in the sides of the bracket whereby the latter is made vertically adjustable; and adjustment of the bracket, when the bolts 108 are loosened, may be made by means of a screw 111 which passes loosely through a hole 107' in the web 107 and is connected at its lower end to the web of the bracket 110, and on its upper end receives an adjusting nut 112.

Rotatably journaled in the lower legs of the H-bracket 110 is a pintle 115, secured to the frame by means of screws 116 or the like and attached to a head 117. This head carries a tubular goose neck 120, terminating in a spout 121, adapted to extend through an opening in the frame 73 for depositing metal in the dies.

Extending rearwardly from the goose neck is another head 124, in which are mounted a pair of pintles 125 (Fig. 2). These pintles are adjustable relative to the head by means of set screws 127, in order that the pintles may be perfectly seated in cam grooves 128 formed in the casting 105, which grooves extend rearwardly and thence upwardly.

It will thus be noted that the goose neck, when moved rearwardly or to the left in Fig. 1 by means of the H-brackets 102 and 110, will be caused to dip downwardly into the receptacle 10, so as to receive a charge of molten metal, pivoting about the axis of the pintle 115 as the pintles 125 are forced upwardly along the cam grooves 128. This motion is reversed when the H-frames are moved to the right, the goose neck then being moved to casting position shown in Figs. 1 and 2. A suitable hose or pipe 122 communicates with the rear end of the goose neck 120 for supplying compressed air or other fluid under pressure into the goose neck and thus forcing the metal therefrom into the die.

The operation of the machine is substantially as follows: The shaft 17 having been set in operation, motion is transmitted to the bevel gear 18. When the clutch member 21, keyed to the shaft 20, is moved by means of the hand lever 29 into engagement with one

or the other of the bevel gears 19 or 19', motion is transmitted through the spur gears 32, 33 and 32', and 33' to the worm wheel 38, the direction of rotation of this worm wheel and its shaft depending upon which of the bevel gears 19 and 19' happens to be clutched.

Assuming that the parts are in the position shown in Fig. 3, rotation of the shaft 39 by the worm wheel 38 causes the crank pin 47, through the cam plate 50 and the connections of the latter to the movable die, to first move the movable die member toward the fixed die member, but before said die members are brought together the pin 47 acting on the cam plate 51, through the connections from the latter to the core members, moves the latter into operative position between the die members. The same half revolution of the shaft 39, through the pin 88 and cam plate 91 and connections therefrom to the goose neck 120 shifts the latter from its outward elevated position to the position shown in Fig. 1, thereby loading the goose neck with a charge of molten metal. At the conclusion of these movements (effected by a half revolution of shaft 39) the driving clutch is automatically thrown to neutral by one of the pins 40 on the worm gear, the compressed air is turned on through hose 122, and the charge of molten metal is forced into the die. As soon as the casting in the die has cooled sufficiently to be withdrawn, the operator throws the clutch into engagement with the other bevel wheel, and the shaft 39 is rotated a half revolution in the reverse direction. This first withdraws the core members, and then retracts the movable die member 78 to the position shown in Fig. 3; and the same reverse semi-rotation of the shaft 39 shifts the goose neck charger rearwardly to its loading position. Near the conclusion of the die separating movement, the ejector 69 comes into contact with the fixed bar 61 and thereby ejects the work from the movable die member 68. By means of the adjusting screws 61', which determine the position of the ejector abutment bar 61, the point at which the ejector begins to act can be accurately determined. At the conclusion of these movements the machine is again automatically stopped by one of the pins 40 coming in contact with the lug 42 on the clutch shift lever; the casting is removed from between the die members, and the described cycle is then repeated. The object of the automatic interruption in the motion of the parts is to permit a delay of any desired period after the die has been charged, in order that the metal may set. Since this period will vary according to the type of work, it is intended that an operator shall determine the time which is to lapse before resuming the operation, the resumption being effected by manipulation of the hand lever 29, as described.

Various modifications and improvements coming within the spirit of my invention will doubtless occur to those skilled in the art. Hence, I do not wish to be limited to the specific form disclosed or uses mentioned but reserve all such modifications and changes as fall within the scope of the appended claims, which are to be interpreted as broadly as the state of the art permits.

49 I claim:

1. In a die casting machine, in combination, a stationary die, a movable die, a core movable into and out of said dies, a channel-shaped member having a cam slot in the web portion thereof, a cam plate slidably mounted in said channel-shaped member and also having a cam slot therein, means connecting one of said cam members to said movable die, means connecting the other of said cam members to said core, and means for actuating said cam members comprising a rotary device and a pin positioned eccentrically on said rotary device and extending through and engaging both of said cam slots.
2. In a die casting machine, in combination, a stationary die, a movable die, a core movable into and out of said dies, a channel-shaped member having a cam slot in the web portion thereof, a cam plate slidably mounted in said channel-shaped member and also having a cam slot therein, means connecting one of said cam members to said movable die, means connecting the other of said cam members to said core, and means for actuating said cam members comprising a rotary device and a pin positioned eccentrically on said rotary device and extending through and engaging both of said cam slots, one of said cam slots having a portion arcuate in form on a radius equal to the radius of said eccentric pin and concave in one direction, the slot in said other cam member having a portion of substantially equal curvature and concave in the opposite direction.
3. In a die casting machine, in combination, a stationary die, a movable die, a core movable into and out of said dies, a first plate having a cam slot therein, a second plate slidably mounted adjacent said first plate and also having a cam slot therein, means connecting one of said cam plates to said movable die, means connecting the other of said cam plates to said core, and means for actuating said cam plates comprising a rotary device and a pin positioned eccentrically on said rotary device and extending through and engaging both of said cam slots, one of said cam slots having an arcuate portion on a radius equal to the radius of said eccentric pin and concave in one direction, the slot in said one cam plate having a portion of substantially equal curvature and concave in the opposite direction.
4. In a die casting machine, in combination, dies, cores slidably mounted for move-

ment into and out of the mold formed by the dies, and means for supporting and actuating said cores comprising a slide adjustable vertically of said dies, a member movable horizontally on said slide and carrying a core, a rack on said member, an elongated pinion meshing with said rack and effective to actuate the rack in all positions of the slide, means for rotating said pinion comprising a second rack movable into and out of engagement with said pinion so as to provide a lost motion connection therebetween, means for reciprocating said second rack comprising a cam plate connected thereto, and a rotatably mounted crank having a pin engaging a slot in said cam plate.

5. In a die casting machine, in combination, dies, cores slidably mounted for movement into and out of the mold formed by the dies, and means for supporting and actuating said cores comprising a slide adjustable vertically of said dies, a member movable horizontally on said slide and carrying a core, a rack on said member, an elongated pinion meshing with said rack and effective to actuate the rack in all positions of the slide, means for rotating said pinion comprising a second rack movable into and out of engagement with said pinion so as to provide a lost motion connection therebetween, and means for reciprocating said second rack.

6. In a die casting machine, in combination, dies, cores slidably mounted for movement into and out of the mold formed by the dies, and means for supporting and actuating said cores comprising a slide adjustable vertically of said dies, a member movable horizontally on said slide and adapted to carry a core, a rack on said member, an elongated pinion meshing with said rack and effective to actuate the rack and in all positions of said member, and means for rotating said pinion.

7. In a die casting machine, in combination, a stationary die, a movable die, a core movable into and out of said dies, a first plate having a cam slot therein, a second plate slidably mounted adjacent said first plate and also having a cam slot therein, means connecting one of said cam plates to said movable die, means connecting the other of said cam plates to said core, and means for actuating said cam plates comprising a rotary device and a pin positioned eccentrically on said rotary device and extending through and engaging both of said cam slots.

8. In a die casting machine, in combination, a stationary die, a movable die, a movably mounted container for supplying metal to the die, a core movable into and out of the die, means for actuating said parts in timed relation comprising a first cam plate connected to said movable die, a second cam plate connected to said container, and a third cam plate connected to said core, a rotatably

mounted shaft, a crank on said shaft carrying a pin engaging slots in said first and second cam plates, and a second crank on said shaft carrying a pin engaging in a slot in said third cam plate.

9. In a die casting machine, in combination, a support, a stationary die mounted on said support, a gooseneck for dipping molten metal from a container and having a nozzle movable into register with an opening in said die, means for mounting said gooseneck comprising a pair of laterally spaced horizontally extending slide bars, a carrier slidably mounted on said bars for movement toward and from said die, a bracket adjustable vertically on said carrier, a member pivotally mounted on the lower end of said bracket and secured to the other end of said gooseneck, a cam follower on said gooseneck, and a cam slot from said follower mounted on said support and having a portion parallel to said slide bars in which the follower moves while the nozzle is being inserted into and withdrawn from said die, the remainder of said cam slot being curved and inclined upwardly so as to dip the gooseneck after the nozzle has been withdrawn horizontally, and means for actuating said carrier.

10. In a die casting machine, in combination, a support, a stationary die mounted on said support, a gooseneck for dipping molten metal from a container and having a nozzle movable into register with an opening in said die, means for mounting said gooseneck comprising a pair of laterally spaced horizontally extending slide bars, a carrier slidably mounted on said bars for movement toward and from said die, a bracket adjustable vertically on said carrier, a member pivotally mounted on the lower end of said bracket and secured to the other end of said gooseneck, a cam follower on said gooseneck, and a cam slot for said follower mounted on said support and having a portion parallel to said slide bars in which the follower moves while the nozzle is being inserted into and withdrawn from said die, the remainder of said cam slot being curved and inclined upwardly so as to dip the gooseneck after the nozzle has been withdrawn horizontally, and means for reciprocating said carrier.

11. In a die casting machine, in combination, a support, a stationary die mounted on said support, a gooseneck for dipping molten metal from a container and having a nozzle movable into register with an opening in said die, means for mounting said gooseneck comprising a pair of laterally spaced horizontally extending slideways, a carrier slidably mounted on said ways for movement toward and from said die, a bracket adjustable vertically on said carrier, means pivotally mounting the other end of said gooseneck on the lower end of said bracket, a cam follower on said gooseneck, and a cam slot

for said follower mounted on said support and having a portion parallel to said slideways in which the follower moves while the nozzle is being inserted into and withdrawn from said die, the remainder of said cam slot being curved and inclined upwardly so as to dip the gooseneck after the nozzle has been withdrawn horizontally, and means for actuating said carrier.

12. In a die casting machine, in combination, a stationary die, a movable die, a core movable into and out of said dies, a molten metal container, a movably mounted gooseneck for dipping molten metal out of said container and having a nozzle movable into register with an opening in said dies, and means for actuating said movable parts comprising independently movable cam plates connected one to each of said movable parts and having cam slots therein, and means for actuating said cam plates comprising a rotatably mounted shaft, a pair of crank pins supported eccentrically on said shaft, one of said crank pins engaging in one of said cam slots and the other of said crank pins engaging in the other cam slots, and means for rotating said shaft, said cam slots having arcuate middle portions and substantially straight end portions extending transversely of the path of movement of the cam plates.

13. In a die casting machine, in combination, a stationary die, a movable die, a core movable into and out of said dies, a molten metal container, a movably mounted gooseneck for dipping molten metal out of said container and having a nozzle movable into register with an opening in said dies, and means for actuating said movable parts comprising independently movable cam plates connected one to each of said movable parts and having arcuate cam slots therein, and means for actuating said cam plates comprising a rotatably mounted shaft, a pair of crank pins supported eccentrically on said shaft at a radius approximately equal to that of said slots, one of said crank pins engaging in one of said cam slots and the other of said crank pins engaging in the other cam slots, and means for rotating said shaft.

14. In a die casting machine, in combination, a stationary die, a movable die, and means for actuating said movable die comprising a power driven rotating shaft, a crank on said shaft carrying an eccentric pin, a slidably mounted plate having a cam slot in which said pin is positioned, said cam slot having a central portion arcuate in form on a radius equal to the radius of said eccentric pin and substantially straight end portions extending transversely of the direction of movement of said plate, and means connecting said cam plate to said movable die.

EDWARD HOTTER.
